United States Patent Office.

J. HENRY HERMAN, OF BOSTON, MASSACHUSETTS.

Letters Patent No. 77,089, dated April 21, 1868.

IMPROVED RAILROAD-RAIL.

The Schedule referred to in these Letters Patent and making part of the same.

TO ALL WHOM IT MAY CONCERN:

Be it known that I, J. HENRY HERMAN, of Boston, in the county of Suffolk, and State of Massachusetts, have invented an Improvement in Rails for Street-Railways, of which the following is a full, clear, and exact description, reference being had to the accompanying drawings, making part of this specification, in which—

Figures 1 and 2 are perspective views of rails having my improvement applied thereto.

Figure 3 is a section on the line $z-z$ of fig. 1.

Considerable difficulty is often experienced in replacing street-railroad cars upon the track when accidentally thrown off, and it frequently becomes necessary to draw them for a long distance over the pavements before the wheels will take the proper direction to insure their running up on to the rails, thus severely jolting the passengers, and tending to injure and strain the car and the horses.

This invention has for its object to overcome these difficulties, and afford a ready and convenient means of replacing the cars upon the track; and consists in a rail provided on one or both sides with a projection, having an inclined groove leading up on to the rail for the purpose of receiving and guiding the flanges of the car-wheels into their proper position upon the track.

To enable others skilled in the art to understand and use my invention, I will proceed to describe the manner in which I have carried it out.

In the said drawings, A, fig. 1, represents an ordinary street-railroad rail, of that description usually laid down in paved streets. On the outside of this rail is formed a projection, a , which is curved or inclined outward from the point 4 to the point 5, and upward from 5 to 6, where it is provided with a groove, b , which also extends across a portion of the upper surface of the rail.

When a car has been thrown from the track, and it is desired to replace it, it is merely necessary to drive it up close to the rail, so that the flange of one of the wheels will strike the projection a at the point 5, when it will follow the inclined groove b up into its proper position upon the rail, the wheel at the other extremity of the axle at the same time striking a grooved projection, c , on the inside of the opposite rail, which serves to guide it into its place in a manner similar to the projection a . As each rail is provided on its outer side with one of these grooved projections, a , it will be seen that it is only necessary to drive the car, when off the track, a very short distance in order to cause one of the wheels to come into contact with a projection which will insure its being replaced upon the track, thus avoiding the necessity of drawing the car for a long distance over the pavements, as is frequently the case where the ordinary rails are employed. The groove b may, if desired, be made to extend only as far as the outer edge of the rail, instead of across it, as seen in the drawing. The angle, however, at which it crosses the rail is sufficiently acute to prevent the wheel from dropping into the groove during the ordinary passage of a car, and the concussion is therefore so slight as to be hardly perceptible. The grooved projection c , on the inside of the rail, may be dispensed with, if desired, as that a , on the outside, will answer well if used alone. In fig. 3 is represented a T-rail, having my improvement applied thereto, the projections d and e being similar to those on the rail A, above described.

Claim.

What I claim as my invention, and desire to secure by Letters Patent, is—

A railroad-rail, having an inclined projection on one or both sides, provided with a groove, for the purpose of guiding the car-wheel up into its proper position upon the track, substantially as set forth.

J. HENRY HERMAN.
